UNITED STATES PATENT OFFICE

2,517,147

SILENCER FOR PRINTING TELEGRAPH APPARATUS

Richard F. Vee, Chicago, Ill., assignor to Teletype Corporation, Chicago, Ill., a corporation of Delaware

Application September 30, 1948, Serial No. 52,077

7 Claims. (Cl. 178—42)

1

This invention relates to printing telegraph apparatus and more particularly to mechanism for silencing a telegraph printer.

There has been considerable effort directed towards the silencing of printing telegraph apparatus. There are two main directions in which such effort has been applied. First, telegraph printers have been designed to include a minimum number of moving parts which provide the source of most of the noise connected with printing telegraphy. Second, it has been proposed to house the printers in soundproof cabinets or in soundproof rooms. Obviously, with a machine which necessarily must be as complicated as a telegraph printer, it is only possible to reduce the noise to a certain point and it is impractical to make the printer itself silent. Therefore, it is but natural to enclose the printer in some type of a silencing cabinet.

When telegraph printers have been placed in soundproof rooms they have been very effectively silenced, however, it is bothersome for an operator to continually enter a separate room in order to pick up telegraph copy. Therefore, perhaps the greatest efforts have been expended towards the design of an effective soundproof cabinet. It is a comparatively easy matter to completely enclose a telegraph printer in a small cabinet and thereby silence it; however, difficulties have been encountered in providing for the continuous withdrawal of a work sheet or the copy from within such a cabinet without destroying the effectiveness of the cabinet as a silencer. Numerous attempts have been made to seal off the paper exit slot except for the protruding paper or work sheet, but in doing this it becomes almost a necessity that means be provided outside the printer for positively withdrawing the work sheet or strip. Naturally this is expensive.

It has been found that the noise actually escaping from the cabinet through the air space in the paper exit slot of a soundproof telegraph printer cabinet is practically nil, and that nearly all of the noise escaping results from vibrations induced in the paper strip, the vibrations traveling to the outside of the cabinet along the paper strip.

The principal object of the present invention is therefore to provide means for damping the vibrations induced in the work sheet or paper strip by a telegraph printer prior to the exit of such strip from a silencing cabinet.

Other objects and advantages of the invention will appear from the following detailed de-

scription when read in conjunction with the accompanying drawings wherein:

Fig. 1 is a side elevational view of a telegraph silencing cabinet partly cut away to show more clearly the principal features of the invention;

Fig. 2 is a detail view of the apparatus for dampening vibrations induced in a work sheet; and

Fig. 3 is another detail view of the vibration dampening means.

In the drawings a cabinet 11 is lined with suitable soundproofing insulating material 12. The top central portion of the cabinet 11 is cut away as shown and has a glass viewing plate 13 therein. The viewing plate 13 is hinged to the cabinet 11 and is mounted so as to provide a paper exit slot 14. Mounted suitably within the cabinet 11 is a telegraph printer 16, the printer having a cylindrical platen 17 around which a work sheet or paper strip 18 travels. Suitable means (not shown, such as rollers) are provided for maintaining the paper strip 18 in engagement with the platen 17. The printer 16 is also provided with a plurality of type bars, represented by a single type bar 19, all of which are adapted to strike against the paper strip 18 as it travels around the platen 17 in order to cause intelligence to be printed on the paper. After the paper 18 travels around the platen 17, and after having received intelligence thereon, the paper travels through the slot or paper exit 14 to the outside of the cabinet 11.

A pair of brackets 21 are secured suitably to the printer 16 and support a plate 22 by means of bolts 23. A pair of brackets 24 are secured suitably to the plate 22 and each support pivotally an arm 26 by means of a bolt 27. The arms 26 are urged clockwise about the bolts 27 by means of springs 28. The arms 26 support, parallel to the platen 17, a rotatable shaft 29 which carries a plurality of discs or rollers 31. The effect of the springs 28 is to continuously urge the rollers 31 towards the platen. The plate 22 has a pair of projections 32 which support a rotatable shaft 33 parallel to the platen 17. Mounted on the shaft 33 are a plurality of discs or rollers 34. The rollers 31 are spaced uniformly along the shaft 29 and the rollers 34 are spaced uniformly along the shaft 33 midway between the rollers 31.

Turning to Figs. 1 and 3 it is apparent that the two sets of rollers 31 and 34 overlap one another slightly. The paper strip 18, as it leaves the platen 17, passes between the two sets of rollers 31 and 34 and due to the overlap between

the two sets of rollers the paper strip 18 is wrinkled longitudinally slightly. When one of the type bars 19 strike the paper 18 while against the platen 17, considerable vibration is set up in the paper. These vibrations are known as type chatter. When the paper 18 extends out of the cabinet 11 the type chatter is transferred along the paper. However, when the paper 18 is wrinkled longitudinally by the two sets of rollers 31 and 34 the type chatter is reduced to a minimum due to the damping of the vibrations in the paper 18. The noise normally transferred by the paper strip 18 is, therefore, effectively reduced.

By the present invention there is provided a very efficient mechanism for minimizing the noise from telegraph printers or other printing machines having means for striking a work sheet to impress intelligence thereon. The invention has been described in connection with a single operative embodiment but it is to be understood that modifications may readily occur to those skilled in the art without departing from the spirit or scope of the invention.

What is claimed is:

1. In an apparatus for silencing telegraph apparatus, a soundproofing cabinet for enclosing the telegraph apparatus, said soundproofing cabinet having a paper exit, a plurality of type pallets in said telegraph apparatus for printing intelligence on a paper strip, and means mounted within said cabinet for wrinkling said paper strip prior to passing through said exit, whereby vibrations induced in the paper by said type pallets striking are damped.
2. In an apparatus for silencing telegraph apparatus, a cabinet for enclosing a telegraph printer, said cabinet being effective to dampen noise from said printer and having a paper exit therein, a plurality of type pallets in said printer for printing intelligence on a paper strip, and a wrinkler for dampening vibrations induced in said paper strip by said type pallets to prevent chatter in said paper strip after passing through said paper exit.

3. The combination of a cylindrical platen, means for supporting a work sheet against said platen, and a pair of sets of discs for longitudinally wrinkling said work sheet to dampen vibrations induced therein when type pallets strike said work sheet while against said platen.

4. In an apparatus for silencing telegraph printers, a substantially soundproof cabinet for housing a telegraph printer, said cabinet having a paper exit slot, and means mounted on said printer for wrinkling longitudinally a paper advancing through said printer to prevent vibrations having been set up in said paper by said printer from continuing in said paper after passing through said paper exit slot.
5. In an apparatus for silencing telegraph printers, a substantially soundproof cabinet for housing a telegraph printer, said printer having a plurality of type bars for printing intelligence on a paper strip, said cabinet having a paper exit, and a pair of sets of rollers secured to said printer and being positioned such that said paper strip having received intelligence thereon is directed between said sets of rollers and longitudinally wrinkled thereby to dampen vibrations set up in said paper strip by said type bars prior to the exit of said paper strip through said paper exit.
- 10 6. In combination with a telegraph printer having a rotatable platen, means for advancing a paper strip around said platen, a plurality of type pallets for printing intelligence on said paper strip by striking said paper strip while against said platen, and a pair of sets of overlapping rollers for wrinkling said paper strip longitudinally to dampen vibrations set up therein by said type pallets when striking said paper strip while against said platen.
- 15 7. In an apparatus for printing intelligence on a work sheet, printing means for striking a work sheet to impress intelligence thereon, and a pair of sets of cooperating overlapping rollers for wrinkling said work sheet subsequent to the impression of intelligence thereon by said printing means in order to suppress noise induced in said work sheet by the striking thereof by said printing means.
